FIG. 4.

UNITED STATES PATENT OFFICE.

FRANCIS C. OSBORN, OF DETROIT, MICHIGAN, ASSIGNEE, BY MESNE ASSIGNMENTS, TO THE
NATIONAL CASH REGISTER COMPANY, OF DAYTON, OHIO, A CORPORATION OF OHIO,
(INCORPORATED IN 1896.)

CASH-REGISTER.

No. 861,312.

Specification of Letters Patent.

Patented July 30, 1907.

Application filed October 22, 1901, Serial No. 79,552.

To all whom it may concern:

Be it known that I, FRANCIS C. OSBORN, a citizen of the United States, residing at Detroit, in the county of Wayne and State of Michigan, have invented certain new and useful Improvements in Cash-Registers, of which I declare the following to be a full, clear, and exact description.

My invention relates to improvements in cash registers.

10 The special features of my improvements will be more particularly hereinafter pointed out, especially in the appended claims.

Referring to the accompanying drawings, Figure 1, is a vertical section through the complete machine. Fig. 2 is a similar view, showing the cash drawer partly open and the other parts in corresponding positions. Fig. 3 is a detail view of the gear and connections employed to actuate the indicator resetting frame looking in the direction of the arrow shown in Fig. 2. Fig. 4 is a rear 20 elevation view of the machine.

In my machine the value keys are employed partly as setting means. That is to say, the indicators and the registering-wheels are not moved directly by the keys, and the operation of any key so adjusts its indicator 25 that the subsequent movement of the till-cover will move the registering-wheels and expose the tablet belonging to that particular operated key.

In the drawings, the numeral 10 indicates the fixed frame of the machine, in which is supported the key shaft 11, upon which the keys 12 are hung. The keys, as usual, are in the form of levers and have their rear ends 13 extending back and downward. Carried by each key is a socket, within which fits and slides a pointed spring-actuated plunger 14, which co-operates with a flat-sided bar 15. This arrangement is well known and is for the purpose of retaining a key in either position to which it may be moved. If a key has been moved, it retains it in its position. If the key be moved back to normal position, the plunger retains it there against unintentional displacement.

There is of course one indicator 16 to each key. Each indicator is carried by an indicator-rod 17, which is formed preferably of a piece of sheet metal by bending up the edges so that the indicator-rod is U-shaped in cross section. Secured to or formed integral with each indicator-stem, and near their lower ends, are arms 18, one for each indicator-rod. Each arm is secured at its upper end to the indicator-rod. The lower end of each arm is provided with a finger 19 extending almost horizontally toward the front of the machine. There is also one coiled spring 20 to each indicator-rod and each spring is connected at one end to its rod and at the other to the fixed cross-plate 21. As these springs are always under tension, the indicator-rods are at all times under

spring tension tending to throw them into an elevated 55 position; or in other words to raise them to indicating position. Such movement, however, is normally prevented by the fact that the fingers 19 of each indicator, being held toward the front by the spring of the metal of which it is made, engages under the ledge 60 23 of the horizontal indicator cross-bar 22. In Fig. 1 an indicator is shown in normal position with the finger in such engagement.

The rear end 13 of each key-lever is immediately in front of its respective indicator-rod, and the arrangement is such that when a key is pressed its rear end in moving rearward and upward, strikes the indicator-arm 18 and moves it back far enough to disengage the finger 19 from its cross-bar as shown in Fig. 2. It thereupon moves upward a short distance under the impulse of its spring 20 until it strikes and stops against the ledge 24 of the swinging releasing-frame 25. This frame comprises vertical arms 26, which at their lower ends are journaled upon a transverse shaft 27. The indicator which has been thus set by the operation of its 75 key, remains in engagement with the indicator-releasing-frame until subsequently when the till-cover is moved, a pin 28, which is carried by one of the end-plates 29 of the till-cover, strikes a pawl 34 which is pivoted to one of the vertical arms of the indicator-releasing-frame 25. This pawl hangs vertically and is prevented from swinging toward the front of the machine by a stop-pin 35. When, therefore, the pin 28 on the end-plate strikes the pawl, as shown in Fig. 2, it operates to swing the releasing-frame toward the 85 front of the machine until in its inward movement said pin 28 slides up and passes over the pawl 34, whereupon the spring 36 restores the releasing-frame to normal position. During the return movement of the till-cover, the pin 28 strikes the opposite side of the 90 pawl 34, and in swinging it to ondsie, passes by without moving the releasing-frame.

The cash-till 30 is stationary and might be said to be in the form of a pan, having suitable partitions to form the coin and bill compartments. At either end is a 95 semi-circular vertical wall 31, extending above the till to hide the mechanism. Between each of the two semi-circular walls and its adjacent side-frame 10, is located one of the two end-plates 29 of the till-cover, one of which is shown very clearly in Fig. 2. Each 100 plate has secured to it and projecting outward, a short shaft or trunnion 32, which is journaled in suitable bearings, one of which is secured to the inner side of each side-arm 10. The till-cover 33 is secured to the front circular edges of the end plates 29. Therefore, 105 the till-cover, as well as the end-plate, may be swung with the trunnions as a center. In this manner the operation of a key sets its indicator, and the subsequent

operation of the till-cover releases it, whereupon it is projected into indicating position by its spring 20. The indicators are restored to normal position through the operation of the till-cover when the next registration is made. To this end there is provided the indicator-restoring-frame, comprising the horizontal cross-bar 37 and two vertically reciprocating slide bars 38. The restoring-frame co-operates with the shoulders 39, one of which is formed upon the rear side of each indicator-stem below the cross-bar 37 of the restoring-frame. When an indicator is projected into indicating position, it is stopped by the abutment of the shoulder 39 against the cross-bar 37 of the restoring-frame. Therefore, to return all of the indicators to normal position, I have simply provided a connection between the till-cover and the restoring-frame so that the cross-bar 37 is reciprocated down and then back at each operation of the machine, and in so moving, it forces all of the operated indicators downward so far that their fingers 19 engage under the ledge 23 of the indicator cross-bar 22 and thereby retain the indicators in normal position.

The connection between the till-cover and the restoring-frame comprises two segment-racks 40, one of which is formed on each end-plate 29. The segment-racks 25 respectively engage the gears 41 journaled on the stud-shafts 42, one of which is secured to each side-frame 10. There are two disks 43, one adjacent each gear 41, and there are two spring-pressed pawls 44, one pivoted to each disk and engaging a notch in the circular plate 30 45 (Fig. 3) which is secured to and is movable with the gear 41. When, therefore, the segment-rack 40 moves the gear 41, the plate 45 moves with the gear, and through the pawl 44 turns also the disk 43. A crank-plate 46 is secured against the outer side of the gear 41 and moves with the disks 43 as they are mounted on opposite ends of the sleeve 47 on the stub-shaft 42. A duplicate of the construction shown in Fig. 3 as applied to the right-hand side-frame is also applied to the left-hand side-frame of the machine, but the description of 40 one will suffice for both.

A link 48 connects the crank-plates 46 with their adjacent slide-bars 38 of the restoring-frame. Under this construction, it results that whenever the till-cover is opened and closed, the gear 41 is given a complete rotation in one direction, and then another complete rotation in the opposite direction. Starting from normal position, the disk 43, and consequently the crank-plate 46, makes a complete turn in one direction of the gear and then stops, because, of course, the pawl 44 slips during the movement in the opposite direction and simply rides idly over the periphery of the plate 45. As shown in Fig. 1, the stop-pawl 49 engages against the shoulder 50 of the disk 43 and holds these parts in normal position and positively prevents 55 reverse rotation of the crank-disk. In this manner the restoring-frame is reciprocated once at each operation of the machine and restores to normal position those indicators which were raised or exposed during the preceding operation of the machine.

60 A key when depressed remains in that position until it is returned by the resetting-frame, comprising side-arms 51, the upper cross-bar 52, and the stud or projection 53. The side-arms are pivoted at their upper ends on the key-shaft 41. The stud or projection 53 lies in 65 the path of a cam projection 54 on the end-plates 29 and

as the cross-bar 52 underlies all of the keys, it results that at about the time when the till-cover is fully open, the cam projection 54 strikes the stud 53, thereby swinging the resetting-frame upward, and the cross-bar 52 by contact forces all of the operated keys to normal 70 position. I provide a very simple form of full-stroke device, which consists of a curved latchet-bar 55, which is secured to the stationary side-frame of the machine. Co-operating with it is the usual spring-pressed pawl 56, which is pivoted to the movable end-plates 29, and compels a full stroke in both directions. A duplicate of this full-stroke device shown may be applied to the other side of the machine if desirable.

The drawer-latch 57 is pivoted to the side-frame. At its rear end it is connected by a coiled spring 58 with the side-frame of the machine. Its front end is provided with a cross-plate 59 lying just under one of the side-arms 51 of the resetting-frame. Carried by the drawer-latch near its front end also, is the tooth 60, which co-operates with the toothed ridge 61, which is secured to and carried by the end-plate 29. The latch, therefore, engages the teeth of the ridge 61 before the drawer is entirely closed. The till-cover can only be unlocked by depressing a key. Heretofore in some machines of the class described, it is as possible to press a key far enough to release the cash-drawer, and then after the cash-drawer was released, to return the key to normal position, and the drawer could be then operated without making any indication, but with my machine this is impossible because the key must be held depressed until the ridge 61 has passed entirely clear of the nose 60, and by that time the key cannot be manipulated so as to defraud the machine.

The detail adding wheels 64 are all strung on the wheel-shaft 65, which is supported at its ends in the side-frames. There is of course one adding wheel for each key, and each wheel is provided with a friction-disk 66 also strung on the wheel and bearing against the sides of their respective adding wheels. Under this construction of course the wheels can turn on the wheel-shaft, but they have a frictional engagement therewith and if said-shaft be rocked, in the absence of detents the wheels will all turn with the shaft, and this is the operation of my machine.

At or near the right-hand end of the wheel-shaft 1 110 provide a crank-arm 67 fast upon said shaft and having a stud 68 upon its swinging end. One of the trunnions 32 is in like manner provided with a similar crank-arm 69, having a stud 70. The pitman 71 is pivoted at its lower end to the crank-arm 69 and at its upper end it 115 has a slot 72 in which the stud 68 plays. It results from this construction that whenever the till-cover is opened and closed, the wheel-shaft, with all of the wheels thereon, is rocked a short distance in one direction and then back to normal position. All of those 120 adding wheels, except the ones that co-operate with the operated keys, are idly rocked from normal position and then back again. The registering-wheels, which co-operate with the operated keys, are also rocked from normal position, but are not returned with 125 the others as they are held in their moved positions and the wheel-shaft simply turns within them, thus leaving each wheel advanced the distance of one tooth.

The detent means consists of a series of detents 73, one of which is carried by each indicator-stem. By 130

reference to Fig. 1, it will be seen that ordinarily these detents are each far below and out of the path of its respective adding wheel. When the indicator-stem, however, is released and thrown upward by its spring, 5 it rises until its detent engages its respective adding-wheel. Therefore, when all of the adding wheels are swung in the direction of the arrow (Fig. 1) by the rocking of the wheel-shaft, the detent 73 engages ahead one tooth and prevents the return of its adding-wheel 10 when all the others are swung backward to the positions from which they were moved.

Several of the parts shown in connection with my present invention have also been shown, described and claimed in my co-pending application No. 560,326. 15 This is especially true of the latch for the till cover and the parts coöperating therewith.

Having thus described my invention, I claim as new and desire to secure by Letters Patent:

1. In a cash register, the combination with a series of indicators, springs for moving the indicators to indicating position when released, a detent for holding the indicators in normal position, a series of keys for determining the indicators to be exposed, a cash till, a movable cover for the same, and means controlled by the till cover for returning the indicators to normal position. 20
2. In a cash register, the combination with a cash till of spring-activated indicators, a detent for holding the indicators in normal position against their spring tension, a series of keys for predetermining which indicator shall be moved to indicating position, and means for releasing the indicators which coöperate with the operated keys upon the opening of the cash till. 30
3. In a cash register, the combination with the indicators normally under spring tension, a series of value keys, a cash till, a double detent for holding the indicators in normal position against their spring tension, means operated by the keys for disengaging the indicators from one of the detents, a till cover, and devices controlled by the till cover for releasing the indicators from the second 40 detent.
4. In a cash register, the combination with the indicators, each under spring tension, detent means for holding them in normal position against their spring tension, a series of keys for predetermining which indicator shall be moved to indicating position, a cash till and means where by the indicators are released and permitted to move to indicating position during the opening movement of the cash drawer or till. 45
5. In a cash register, the combination with the indicators, each normally under spring tension tending to move it into indicating position, a detent means for holding the indicators in normal position, a series of keys for releasing the indicators from said detent, a second detent for holding the indicators after they have been released from said first detent, means for releasing the indicators from said second detent and allowing them to move to indicating position, and a frame movable independent of the keys and arranged to return the operated indicators to normal position, and means to hold them in such position against the tension of their springs. 55
6. In a cash register, the combination with the indicators normally under spring tension tending to move them to indicating position, a common detent for holding all of the indicators in normal position, a series of keys, a cash till having a movable cover, means connected with the keys for predetermining which indicator shall be operated, and means controlled by the till cover for resetting the operated indicators to normal position. 65
7. In a cash register, the combination with the indicators, of detent means for holding the indicators in normal non-indicating position, springs, one connected to each indicator and tending to project them into indicating position, a series of keys arranged to predetermine what indicators shall be moved to indicating position, a movable lever or handle, means controlled thereby for releasing the 75

indicators which coöperate with the operated keys, an indicator-restoring-frame for resetting the operated indicators to normal position, and connections between the frame and the lever or handle, whereby the movement of said handle actuates the indicator-restoring-frame. 80

8. In a cash register, the combination with a series of keys, of a series of corresponding adding wheels mounted upon a rock-shaft, a connection between the keys and the adding wheels for predetermining which adding wheels shall be actuated, an operating lever or handle, means whereby the movement of the lever or handle rocks the adding wheels and the shaft on which they are mounted, and detent means controlled by the keys and arranged to hold in the positions to which they have been rocked the adding wheels coöperating with the operated keys. 85

9. In a cash register, the combination with the adding wheels, of a rock shaft upon which the adding wheels are mounted, a movable cash till or drawer member, connections with the till or drawer member for rocking the rock shaft and the adding wheels thereon from normal position and then back thereto at each operation of the machine, and means controlled by the operated keys to prevent the return movement of the adding wheels which correspond in denomination to the keys operated. 90

10. In a cash register, the combination with a rock shaft, of a series of adding wheels thereon, a lever or handle arranged to rock the shaft and the adding wheels, first, from normal position, and then back thereto at each operation of the machine, and means controlled by the operated keys to prevent the return movement of the adding wheels which correspond in denomination to the keys operated. 100

11. In a cash register, the combination with a rock shaft, of a series of adding wheels thereon, a lever or handle arranged to rock the shaft and the adding wheels, first, from normal position and then back thereto, a series of keys, and means operated thereby to prevent the return to normal position of those adding wheels which correspond in denomination with the operated keys. 110

12. In a cash register, the combination with a rock shaft, a series of adding wheels mounted thereon, a till cover whose movement is arranged to rock the shaft and the wheels thereon away from normal position and then back thereto, a series of keys, and detents coöperating with the adding wheels so as to prevent the return to normal position of those adding wheels which correspond in denomination with the operated keys. 120

13. In a cash register, the combination with a series of indicators normally under spring tension, a series of value keys, a cash till, detents for holding the indicators in normal position, means operated by the keys for disengaging the indicators from one of the detents, and means for disengaging the indicators from the remaining detent when the cash till is exposed. 125

14. In a cash register, the combination with a series of registering elements, of a series of keys, means for giving all of the registering elements a regular excursion upon each operation of the machine, and means controlled by the keys for preventing the return of the desired elements after they have been moved forward. 130

15. In a cash register, the combination with a series of registering wheels, of a series of keys, means for normally rocking the registering wheels first forward and then back again upon each operation of the machine, and means controlled by the keys for preventing the return of the desired registering wheels. 135

16. In a cash register, the combination with a series of registering elements, of a series of indicators, a series of keys, means for normally giving the registering elements a regular excursion upon each operation of the machine, and means controlled by the keys for setting the desired indicators and preventing the return of the corresponding registering elements. 140

17. In a cash register, the combination with a series of registering elements, of a series of keys, a cash till, means for normally giving the registering elements a regular excursion when the cash till is exposed, and concealed, and means controlled by the keys for preventing the return of the desired registering elements. 145

18. In a cash register, the combination with a series of 15

42

spring impelled indicators, of duplex detent devices, for holding said indicators in unexposed position, a series of keys for releasing the corresponding indicators from the first detent while the second detent still remains effective, and means independent of the keys for controlling the second detent to completely release the indicators to permit the same to move to exposed position.

19. In a cash register, the combination with a series of indicators, springs for moving the indicators to indicating position, a stationary detent for the indicators, and a 10 series of keys for disengaging the indicators from said detent.

In testimony whereof I affix my signature, in the presence of two witnesses.

FRANCIS C. OSBORN.
